(57) **CLAIM**

The ornamental design for a skim board, as shown and described.

DESCRIPTION

FIG. 1 is a perspective view of the skim board showing my new design;

FIG. 2 is a top plan view of the skim board seen in FIG. 1; FIG. 3 is a bottom view of the skim board seen in FIGS. 1 and 2;

FIG. 4 is a center cross-sectional view of the skim board taken on line 4—4 in FIG. 2;

FIG. 5 is an elevation from one side of the skim board with the opposite side being a mirror image thereof;

FIG. 6 is a sectional view taken on line 6—6 in FIG. 5;

FIG. 7 is a rear elevation of the skim board shown in the prior figures; and,

FIG. 8 is a front elevation of the skim board shown in the prior figures.

FIGS. 4 through 8 are shown on an enlarged scale.
